COUNTING MECHANISM FOR LIQUID DISPENSING APPARATUS

Hermann Wydler, Berne, Switzerland, assignor
to the firm Sauser A.-G., Soleure, Switzerland,
a joint-stock company of Switzerland

Application September 8, 1936, Serial No. 99,893
In Switzerland September 13, 1935

4 Claims. (Cl. 221—101)

The present invention relates to liquid dispensing apparatus and more particularly pertains to a counting mechanism for liquid dispensing apparatus comprising a volumetric meter combined with a counter for single deliveries having a zeroizing mechanism and a totalizing counter.

The invention consists in a device associated with the counting mechanism which is set in advance so as to limit the quantity of liquid to be delivered. The setting member is returned stepwise during the dispensing operation to the zero position, and the dispensing apparatus becomes inoperative when the setting member is returned by hand beyond the zero position.

The various objects and features of the invention will be more apparent upon a consideration of the following detailed description and the accompanying drawings wherein an exemplary embodiment of the invention is disclosed.

In the drawings:

Fig. 1 is a sectional view through the casing showing the driving gears developed according to line I—I of Fig. 8.

Fig. 2 is a horizontal sectional view through the casing showing the mechanism with the numeral wheels and supports removed,

Fig. 3 is a vertical sectional view taken on line III—III of Fig. 9,

Fig. 4 is a front view of the apparatus in its inoperative position,

Fig. 5 is a vertical sectional view taken on line V—V of Fig. 9,

Figs. 6 and 7 are detail views relating to the driving gear,

Fig. 8 is a vertical sectional view taken on line VIII—VIII of Fig. 9,

Fig. 9 is a sectional view illustrating the assembly of the apparatus and

Fig. 10 is a sectional view taken on line X—X of Fig. 9 showing the position of the value operating parts when the setting pointer is at zero.

According to Figs. 1, 5 and 8 a hub 102 is rotatably arranged on one of the studs 26 which extend between and connect the plates 21 and 22 of the casing. A pinion 103, having a gap 106 in its periphery is attached to the hub 102 and a cam 104 and a pinion 105 are also secured thereto. The pinion 105 meshes with a pinion 107 fixed to a shaft 108 and a pinion 109, keyed to the shaft 108, meshes with the gear teeth 111 provided adjacent one end of a shaft 110. This shaft is rotatably mounted in a support 112 and the plate 21 and the opposite end is provided with gear teeth 113 meshing with the gear teeth 114 arranged on the inner edge of a ring member 11

having an annular member 116 rotatably arranged therein. A handle 115 serves for turning the ring 117 and acts as a setting index. The annular member 116 is provided with graduations 116 to indicate the quantity of liquid to be delivered and determined in advance. A pin 117 extending from the annular member 116 serves as a stop for the handle 115 to mark the inoperative position of the apparatus.

A shaft 29 is journaled in the plates 22 and 23 (Fig. 1) and is connected by means of the coupling members 28, 8 and a shaft 6 to the volumetric meter 1 which operates the single deliveries counter through the shaft 29. The shaft 29 carries a pinion 30 which meshes with a pinion 31 attached to a shaft 32 and drives this shaft in a determined ratio of transmission. The shaft 32 carries a helical gear 41 which as shown in Fig. 9 drives the shaft 43 carrying a four tooth pinion 44 to operate stepwise the numeral wheel 45 of a counter shown generally at 18 for the single deliveries.

In Fig. 4 the zero numerals of three numeral drums of the single deliveries counter are visible in three openings 200 of the dial, while the totalizing counter 300 is shown in the lower part of the dial and visible through an opening therein.

The shaft 32 also carries a pinion 32a meshing with a pinion 118. The pinion 118 is secured to a shaft 119 which carries a pinion 120 meshing with the teeth of a gear wheel 121 rotatably arranged on a shaft 122. The gear wheel 121 has two rims of teeth, one complete rim of teeth on the right side (Fig. 1) meshes with the pinion 120 and the other rim is provided with only two teeth 123, 123' which mesh during each revolution of the wheel 121 with the teeth of a pinion 124 to turn this pinion only a part of a revolution. The pinion 124 is rotatably mounted on the shaft 119 and has on the right hand side (Fig. 2), where it meshes with the teeth 123 and 123', eight teeth (Fig. 6). The other rim of this pinion has four teeth 124' (Fig. 7), so that a pinion 125 when it is turned cannot mesh with the pinion 124 when the latter is in the position shown. When the pinion 124 however is rotated, it moves also the pinion 125, and a pinion 125a, integral therewith. The pinion 125a meshes with the pinion 103. In order to maintain the pinion 124' when stationary always in the same position relative to the pinion 125 a pawl 126 is pressed by a spring 127 between the teeth of pinion 124.

The cam disk 104 has a boss 128 which at the zero position lifts a roller 129 and thereby actu-

ates a lever 130. The lever 130 is secured to a shaft 131 and the lever 130 is controlled by a spring 132 which tends to press the roller 129 against the periphery of the cam disc 104.

5 The shaft 131 carries an arm 133 (Fig. 3) against which is pressed a roller 134 arranged on an arm 135 of an angular lever 92 which is pivoted on a pin 91 and the other arm 93 of the angular lever 92 serves as a locking bar for an arm 83 of the spring controlled lever 86. The lever 86 is secured to a shaft 82 and the lever arm 83 is urged towards the arm 93 by a spring 84.

The shaft 82 is coupled to a countershaft 12 shown in Figures 9 and 10. This shaft carries 15 a locking pawl 11 adapted to engage the periphery of a disk 7 which is fixed to the meter shaft 6 and controls an arm 13 of a valve 14 for admitting liquid to the meter. In the zero position of the setting index 115 the boss 128 lifts 20 the arm 130 (Fig. 5) and rotates the shaft 131 to swing the arm 93 and unlock the arm 83 (Fig. 3). The arm 83 will then drop so far as will be permitted by an arm 71 which is secured to a shaft 68 and contacts by means of a roller 72 25 with an abutment having a sloping surface 87.

The operating of the setting device is as follows: If it is desired to withdraw some liquid from the dispensing apparatus, the ring 77 is rotated until the setting index 115 marks the desired 30 number on the annular member 76. Thereby the pinion 109 is rotated by means of the pinions 113 and 111. Thus the pinions 107 and 105, the cam disk 104 and the pinion 103 are rotated. The arrangement is such that the disk 104 completes one revolution for one hundred measuring 35 units. Likewise the pinion 125a has been rotated and with it the pinion 125.

The pinion 124 will not be rotated with the wheel 125 because, as is shown in Fig. 7, the 40 pinion 124' is dimensioned for eight teeth but has only four teeth so as to leave gaps between the teeth and allow free passage of the wheel 125.

When the dispensing apparatus delivers liquid, the shaft 29 rotates and the pinion 30 turns the pinion 31 which rotates the shaft 32. The pinion 32a secured to the shaft 32 rotates the pinion 118 and with it the pinion 120. The pinion 120 moves the pinion 121 which at each 45 revolution imparts to the pinion 124 by the teeth 123 and 123' a stepwise movement. At each step of the pinion 124 the pinions 125 and 125a will be rotated one tooth and the wheel 103 will be turned back stepwise. Together with the wheel 103 also the cam 104, wheel 105, wheels 107 and 109, pinion 110 and the setting ring 77 50 will be returned.

As soon as the ring 77 returns to zero the boss 128 of cam 104 will engage the roller 129 and 55 lift it to thus rotate the shaft 131. By this rotation the arm 133 will be moved to actuate the lever 135 by means of the roller 134 and rotate the shaft 91 (Figs. 7 and 3). Thereby the arm 93 moves out of reach of the lever 83 whereupon the spring 84 rotates the shaft 82. Then the arm 11 (Fig. 10) secured to the shaft 12 will drop into the recess 10 of the disc 7 and valve 14 will be closed.

If it is desired to cut out the setting device 60 the index 115 may be moved to pass the zero point in a counterclockwise direction until it is stopped by the pin 117. By doing so the gear wheel 103 will have rotated until the gap 106 causes the gear teeth of the wheels 103 and 125a 65 to be disengaged. Then the shafts 122, 119 and 70

32 which establish the connection with the meter may rotate independently of the setting device.

By moving the index 15 beyond the zero mark the boss 128 of the disk 104 moves out of engagement with the roller 129, and the lever 130 drops upon the rim of the smaller diameter of the disk 104 and the spring 132 rotates the shaft 131 which will withdraw the arm 133 from the roller 134 and release the lever 135 and the arm 93. 10

Since the arm 93 is spring controlled as shown in Fig. 3 it moves as soon as the shaft 82 rotates again and holds the arm 83 and the roller 85 out of engagement with the cam 80 fixed to the shaft 29 by means of a sleeve 81. Thus the 15 delivery position of the apparatus is restored again.

The shaft 82 is coupled to the countershaft 12 which operates the pawl 11 associated with the stop cam disk 7 on the shaft 6 to stop the 20 volumetric meter 1 at the zero position of the single deliveries counter, by actuation of the arm 13 to close the admission valve 14.

If it is desired to withdraw a new supply of measured liquid from the apparatus then the 25 index 115 is again moved to the zero position whereby the wheel 103 will be rotated so far as to be engaged again by the pinion 125a and the setting device can again be operated by the meter as hereinabove described. 30

What I claim as new is:

1. In liquid dispensing apparatus, an annular member having graduations thereon indicating units of liquid to be dispensed, a ring member rotatably mounted with respect to said annular member and having gear teeth along the circumference thereof, an index carried by said ring member, a pinion meshing with the gear teeth of said ring member, a disc having a boss thereon adapted to be rotated upon rotation of the pinion 40 and the ring member to a position corresponding to the units of liquid to be dispensed, a shaft adapted to be rotated when liquid is dispensed, gear means interposed between said disc and said shaft for rotating the disc and the ring member 45 in a reverse direction, and said boss being adapted to engage means for stopping the rotation of the shaft.

2. In liquid dispensing apparatus, an annular member having graduations thereon indicating units of liquid to be dispensed, a ring member rotatably mounted with respect to said annular member and having gear teeth along the circumference thereof, an index carried by said ring member, a pinion meshing with the gear teeth of said ring member, a shaft adapted to be rotated when liquid is dispensed by the apparatus, a disc having means associated therewith for stopping the rotation of said shaft, said disc being geared to be rotated to a given position during movement of the index from the zero position on the annular member, and driving means interposed between said shaft and said disc for returning the index and the disc to the zero position. 50

3. In liquid dispensing apparatus, an annular member having graduations thereon indicating units of liquid to be dispensed, a ring member rotatably mounted with respect to said annular member and having gear teeth along the circumference thereof, an index carried by said ring member, a pinion meshing with the gear teeth of said ring member, a shaft adapted to be rotated when liquid is dispensed by the apparatus, a disc having means associated therewith for stopping the rotation of said shaft, said disc being geared 55

to be rotated to a given position during movement of the index from the zero position on the annular member, and a non-reversible transmission mechanism interposed between said shaft and said disc for returning the index and the disc to the zero position.

4. In liquid dispensing apparatus, an annular member having graduations thereon indicating units of liquid to be dispensed, a ring member 10 rotatably mounted with respect to said annular member and having gear teeth along the circumference thereof, an index carried by said ring member, a pinion meshing with the gear teeth of said ring member, a shaft adapted to be ro-

tated when liquid is dispensed by the apparatus, a disc having means associated therewith for stopping the rotation of said shaft, said disc being geared to be rotated to a given position during movement of the index from the zero position on the annular member, driving means interposed between said shaft and said disc for returning the index and the disc to the zero position, and said driving means including a gear adapted to be turned during the rotation of said disc, said gear wheel having a gap therein adapted to disconnect the driving means when the index is moved to a predetermined position.

HERMANN WYDLER.
